PULVERIZED FUEL BURNER

Robert C. Vroom, Montclair, N. J., assignor to
Peabody Engineering Corporation, New York,
N. Y., a corporation of New York

Application March 10, 1941, Serial No. 382,505

11 Claims. (Cl. 110—104)

This invention relates to burners and more particularly to burners of the type used for burning pulverized coal.

An object of the invention is to provide a burner of the above type in which a uniform distribution of the fuel and air, both across the throat area and around the periphery of the burner throat, is assured.

Another object is to provide a burner of the above type in which the turbulence and mixture of the fuel and air can be readily controlled.

Another object is to provide a burner of the above type in which the influence of the secondary air stream on the helical movement of the stream of fuel and carrier air can be positively controlled.

Another object is to provide a novel and improved burner of the above type wherein the relationship of the fuel stream and secondary air may be controlled as desired.

Another object is to provide a burner of the above type having novel and improved details of construction and features of operation.

Various other objects and advantages will be apparent as the nature of the invention is more fully disclosed.

Although the novel features which are believed to be characteristic of this invention are pointed out more particularly in the claims appended hereto, the invention itself will be better understood by referring to the following description, taken in connection with the accompanying drawings forming a part thereof, in which certain specific embodiments of the invention have been set forth for purposes of illustration.

In the drawings:

Fig. 1 is a longitudinal section through a burner embodying the present invention;

Fig. 2 is a transverse section, taken along the line 2—2 of Fig. 1;

Fig. 3 is a transverse section, taken along the line 3—3 of Fig. 1;

Fig. 4 is a partial longitudinal section similar to Fig. 1 illustrating another embodiment of the invention;

Fig. 5 is a transverse section taken along the line 5—5 of Fig. 4;

Fig. 6 is a partial longitudinal section similar to Fig. 1 illustrating a further embodiment of the invention;

Fig. 7 is a transverse section taken along the line 7—7 of Fig. 6;

Fig. 8 is a transverse section similar to Fig. 2 illustrating a still further embodiment of the invention; and

Fig. 9 is a longitudinal section taken along the line 9—9 of Fig. 8.

In the following description and in the claims certain specific terms are used for convenience in referring to various details of the invention. These terms, however, are to be given as broad an interpretation as the state of the art will permit.

Referring to the drawings more in detail, the invention is shown in Figs. 1 to 3 as applied to a burner comprising an elongated burner tube 10 which is mounted in registration with a burner opening or throat 11 in a furnace wall 12 and is open at its outlet end 10a to the combustion chamber of the furnace. The burner tube 10 is shown as provided with a flange 13 which is secured by any suitable means against the outer surface of the furnace wall 12. The inlet end 10b of the burner tube 10 is provided with a flange 14 secured against the wall 15 of a wind box or plenum chamber 16.

A fuel inlet duct 18 is positioned to admit fuel suspended in carrier air tangentially to the wall of the burner tube 10 through an inlet opening 19 therein. The inlet duct 18 is shown as connected to a fuel supply pipe 20.

A plurality of dampers 21 pivoted on pins 22, may be mounted in the fuel inlet duct 18 so as to control the amount of opening from said duct and/or the direction of flow of the fuel supplied therefrom to the burner tube 10. The dampers 21 are shown as connected to a control rod 24 which extends to the outside of the inlet duct 18 and carries a handle 25 by which adjustment thereof is effected.

The burner tube 10 is shown as provided with a plurality of ribs 28 which form helical channels therebetween within the burner tube for feeding forwardly, as it rotates in the burner tube, that part of the fuel concentrated in the carrier air near the wall of tube 10. The ribs 28 are spaced around the burner tube for distributing this fuel uniformly around the periphery of the burner throat. These ribs may, however, be omitted if, in any particular instance the fuel is caused to advance and is distributed in the desired manner by the flow of air to the furnace.

In the embodiment shown, an inner cylinder 30 is provided which is spaced from the burner tube 10 to form an annular fuel passage 31 therebetween and extends from the inlet end 10b of the burner tube a distance corresponding generally to the length of the opening 19 through which fuel is admitted from the inlet duct 18, although it may be made longer or shorter as desired. The cylinder 30 is shown as carrying

a telescoping sleeve 32 which may be adjusted axially to vary the effective length of the cylinder 30 as desired. The inlet duct 18 and the inlet opening 19 are shown as extending axially over a substantial portion of the length of the burner tube 10 so as to supply the fuel stream thereto in the form of an extended layer which rotates and advances along the inner surface of the wall of the tube 10 in a uniform manner.

Secondary air may be supplied to the cylinder 30 by any suitable means, shown as an air register 35, mounted in the windbox 16 between the wall 15 and a forward wall 38 and having a plurality of peripheral air doors 37 which are adapted to admit a controlled quantity of air to the register and to cause the same to advance axially with a rotary motion. The air register 35 is provided with an axial air discharge opening 38 registering with the open end of the cylinder 30. The air register 35 may be of any standard type and is accordingly not set forth herein in detail.

The cylinder 30 and the sleeve 32 are shown as provided with a plurality of peripherally spaced slots 40 and 41 respectively through which a portion of the stream of carrier air and fuel flows from the annular passage 31 into the interior of the cylinder 30 and is mixed therein with the secondary air received from the air register. By rotating the sleeve 32 with respect to the cylinder 30, the effective size of the slots 40 may be varied, thereby regulating the quantity of carrier air and fuel admitted therethrough. One of the slots 40 is preferably disposed in registration with the inlet opening 19 whereby a portion of the fuel stream received from the inlet duct 18 is caused to pass directly into the interior of the cylinder 30 where it is mixed with the secondary air. The remainder of the fuel, suspended in primary air, flows around the burner tube 10 in the annular passage 31 wherein it is caused to rotate and advance, as above mentioned.

In certain instances it may be desired to burn gaseous or liquid fuel in addition to or in place of the solid fuel above mentioned or to use such gaseous or liquid fuel for ignition purposes. For this purpose, the burner is shown as provided with a fluid fuel supply barrel 42 which extends axially of the burner tube 10 and is provided at its inner end with an atomizer tip 43 of any desired type. A diffuser 44 is likewise mounted on the barrel 42 but may be withdrawn into the air register, as indicated at 44a by dotted lines, when pulverized fuel is burned. The barrel 42 extends outwardly through the air register 35 and may be connected to any suitable source of fluid fuel, not shown.

The centrifugal force produced by the rapidly rotating fuel mixture in the burner tube 10 causes a substantial portion of the heavier fuel particles to hug the surface of the tube. In order to increase turbulence and to throw such fuel toward the axis of the burner, thus distributing it across the burner throat area, a plurality of curved vanes 45 may be provided which may be positioned closely adjacent the wall of the burner tube 10. In the embodiment shown the vanes 45 are adjacent but do not touch the ribs 28. The vanes 45 are shown as mounted on a spider 46 having a hub 47 which is secured to the atomizer barrel 42 by suitable means, such as a set screw 48. The vanes 45 may thus be adjusted axially or angularly to the optimum position.

Operation

In the operation of this device, finely divided fuel, such as pulverized coal, suspended in a stream of primary or carrier air and uniformly distributed therein is received from the feed pipe 20 and passes through the inlet duct 18 and the opening 19 tangentially into the annular passage 31 between the burner tube 10 and the cylinder 30 wherein it rotates in the form of an extended layer. The natural flow toward the furnace and the helical ribs 28 cause the layer of fuel and carrier air to advance through the passage 31 helically toward the burner opening 11 and to be discharged uniformly around the entire periphery of the burner throat. At the same time the secondary air for combustion is received from the discharge opening 38 of the air register 35 and advances axially on the inside of the cylinder 30. Upon leaving the cylinder 30 it mixes with the fuel and carrier air from the passage 31 to form a combustible mixture.

A controlled portion of the fuel may be permitted to pass through the slots 40 into the interior of the tube 30 where it is immediately mixed with the secondary air.

Shortly after the fuel and carrier air have advanced past the end of the cylinder 30 in the form of a rotating mass, a complete mixture with the secondary air takes place and a uniform mixture of fuel and air is advanced to the burner throat for combustion. The desired turbulence and distribution across the burner throat may be aided by the vanes 45 which act as scoops to pick up the rotating mass of fuel and air and to throw the same inwardly toward the axis of the burner, and by the premixing of the secondary air with the portion of the fuel which has passed through the openings 40 into the tube 30. The diffuser 44 may be adjusted in position to assist in controlling the opening of the burner throat and the direction of the air-fuel mixture issuing therefrom or the diffuser may be removed or withdrawn into the air register when desired. The direction of flow of carrier air and fuel supplied to the passage 31 from the duct 18 may be controlled by suitable adjustment of the dampers 21. The degree of rotation of the secondary air may likewise be controlled by making a suitable adjustment of the air doors 37 of the air register 35. The point of direct contact between the carrier and secondary air and the proportion of fuel supplied through the slots 40 to the secondary air stream within the cylinder 30 for premixing may be regulated by suitable axial and rotary adjustment of the sleeve 32. Such adjustment is preferably made by experiment in order to obtain the optimum burner characteristics.

Figs. 4 and 5

The embodiment shown in Figs. 4 and 5 is generally similar to that above described and the description of corresponding parts will not be repeated. In this embodiment the cylinder 50, corresponding to the cylinder 30 of Fig. 1, is shown as provided with a plurality of deflectors 51 which may be stamped out of the cylinder 50 to form slots 52. The purpose of the deflectors 51 is to create an inward flow of fuel and carrier air from the passage 31 to the interior of the cylinder 50, thereby causing a predetermined quantity of fuel to be withdrawn from the passage 31 into the central stream of secondary air. It is to be understood that the deflectors 51 may be varied in shape or position as desired and may

be made adjustable for the purpose of controlling the amount of fuel supplied through the wall of the cylinder 50 to the stream of secondary air.

The cylinder 50 of Fig. 4 is also shown as provided with a set of peripherally spaced apertures 53 at the inlet end 59b thereof to permit a further control of the distribution of the fuel and primary and secondary air. The apertures 53 may be made of any desired size or the end of the cylinder 50 may be spaced inwardly from the end of the burner tube 10 to obtain a similar effect. The apertures 52 and 53 may be used separately or in combination.

Figs. 6 and 7

The embodiment shown in Figs. 6 and 7 is generally similar to the embodiment shown in Fig. 1. In this embodiment, however, the cylinder 55 is made of smaller diameter than the cylinder 30 of Fig. 1 and provides an annular passage 56 of greater cross-sectional area than the passage 31. The cylinder 55 is shown as secured to the air register 35 by brackets 57 and is of smaller diameter than the air register opening 38 so as to afford access for secondary air from the air register opening into the passage 56 as well as into the interior of the cylinder 55.

In this embodiment a portion of the secondary air is admitted directly from the register into the annular passage 56 and is mixed therein with the fuel stream received from the inlet duct 18. This portion of the secondary air also assists in causing the rotating fuel stream to advance axially.

Figs. 8 and 9

In the embodiment shown in Figs. 8 and 9, the influence of the secondary air on the flow of fuel and carrier air is regulated by centrifugal means. In this embodiment, which is generally similar to that above described, the inlet duct 60 is provided with a wall 61 which is positioned beyond the opening 38 of the air register 35 and beyond the burner tube 10 in a radial direction to form a fuel inlet chamber 62 out of the direct path of the secondary air from the air register opening. The wall 61 may be made of an axial length such that it registers with all or a portion only of the inlet duct 60 and joins the burner tube 10 tangentially at a suitable point such as at 63 (Fig. 8).

A fuel inlet chamber 64 is formed by a wall 65 of the duct 60 which joins the burner tube 10 tangentially at a point 66. The chambers 62 and 64 constitute a pair of fuel supply chambers receiving fuel from the inlet duct 60 and delivering the same tangentially to the burner tube 10. The fuel inlet chambers 62 and 64 are joined by a sloping wall 66'.

In the operation of this embodiment, a portion of the stream of fuel and carrier air introduced tangentially from the inlet duct 18 enters the supply chamber 62, wherein the centrifugal force causes the same to hug the wall 61, and to receive a rotary motion while out of direct contact with the secondary air from the air register opening 38. Wall 66' restrains the axial movement of this stream until it has advanced past the point 63. The secondary air stream supplied from the air register 35 near the axis of the burner tube 10 does not make contact with the rotating mass of fuel in the chamber 62 until the air stream has been expanded from the diameter of the air register opening 38 to the diameter of the tube 10. In this embodiment, the portion of the fuel admitted to the chamber 62 and the portion sup-

plied to the chamber 64 may be controlled by adjusting the angular position of the baffles 21. A plurality of fuel inlet chambers of different and graduated diameters may be used if desired, two such chambers 62 and 64 having been shown for purposes of illustration only.

When the fuel is deflected toward the chamber 62 by vanes 21 as in Fig. 9, a greater portion thereof is caused to rotate in said chamber 62 before being brought into contact with the stream of secondary air for combustion. When the vanes 21 are shifted to the right (as seen in Fig. 9) a greater portion of the fuel stream is deflected to the chamber 64 and comes into contact with the stream of secondary air from the register 35 at a different zone. By a suitable adjustment of these above mentioned elements, improved distribution and mixing characteristics may be obtained.

It will be noted that in all of the embodiments above described, a controlled portion of the fuel stream is caused to assume a rotating motion and to travel axially a predetermined distance before it is brought into direct contact with the secondary air for combustion. This permits control of the relative distribution of the fuel and carrier air and the secondary air, thereby providing a more uniform fuel and air distribution at the burner throat.

It is to be understood that the atomizer barrel 42, the vanes 45, and the ribs 28 may be utilized with any of the embodiments above described; also that the helical ribs 22 may be made of various forms as desired.

The present invention, as above described, provides a dependable and efficient burner of the type above indicated, which is well suited for commercial operation. The flame produced thereby is extremely stable and uniform. Although certain embodiments thereof have been shown and described for purposes of illustration, it is to be understood that the invention is not to be limited thereto, but that various changes and modifications may be made therein as will be readily apparent to a person skilled in the art. The invention is only to be limited in accordance with the scope of the following claims.

What is claimed is:

1. A pulverized fuel burner comprising a burner tube having an open outlet end adapted to connect with a combustion chamber, means including an inlet port in the peripheral wall of said burner tube supplying to said burner tube in a direction tangential to the inner surface thereof a stream of pulverized fuel suspended in carrier air, means causing said suspended fuel to advance helically in a peripheral layer in said burner tube to the outlet end thereof, a central axial air admission means including an air register admitting a secondary air stream at the inlet end of said burner tube out of the main path of the peripherally rotating layer of fuel, said air register having peripheral doors to impart a rotary motion to said secondary air stream, and means preventing direct contact between at least the main portion of the rotating stream of secondary air and the main portion of said fuel stream at the inlet end of said burner tube.

2. A pulverized fuel burner comprising a burner tube having an open outlet end adapted to connect with a combustion chamber, an inner tube in said burner tube having walls spaced therefrom to form an annular fuel passage therebetween, tangential fuel inlet means including an inlet port in the peripheral wall of said burner

tube communicating with said annular passage to supply thereto a stream of pulverized fuel suspended in carrier air under conditions to cause said stream to rotate peripherally in said annular passage, means causing said layer of suspended fuel to advance helically in said burner tube, and a central axial air admission means including an air register admitting a secondary air stream at the axis of said inner tube to advance axially therein, said air register having peripheral doors to impart a rotary motion to said secondary air stream, said inner tube preventing contact between said peripherally rotating fuel stream and said rotating secondary air stream at the inlet end of said burner tube.

3. In a pulverized fuel burner as set forth in claim 2, means for adjusting the axial length of said inner tube for thereby controlling the point of contact between said streams.

4. In a pulverized fuel burner as set forth in claim 2, a telescoping sleeve on said inner tube for adjusting the axial length thereof so as to control the point of contact between said streams.

5. A pulverized fuel burner as set forth in claim 2 in which said inner tube is provided with spaced slots to pass a portion of the fuel from the peripherally rotating fuel stream into the secondary air stream within said inner tube for pre-mixing.

6. A pulverized fuel burner as set forth in claim 2 in which said inner tube is provided with spaced slots to pass a portion of the fuel from the peripherally rotating fuel stream into the secondary air stream within said inner tube for pre-mixing, and deflectors carried by said inner tube adjacent said slots to direct the flow of fuel inwardly therethrough.

7. A pulverized fuel burner as set forth in claim 2 in which said inner tube is provided with spaced slots to pass a portion of the fuel from the peripherally rotating fuel stream into the secondary air stream within said inner tube for pre-mixing, and means for adjusting the effective opening of said slots.

8. In a pulverized fuel burner as set forth in claim 2, a set of axial vanes mounted within said burner tube near the periphery thereof and beyond the end of said inner tube, said vanes being positioned to deflect the fuel stream toward the axis of said burner tube so as to distribute the fuel across the outlet end of said burner tube.

9. A pulverized fuel burner comprising a burner tube having an open outlet end adapted to connect with a combustion chamber, a central axial air admission means at the inlet end of said tube including an air register having an air discharge

opening supplying a secondary air stream to said tube to advance axially therein, said air register having peripheral doors to impart a rotary motion to said secondary air, a fuel inlet duct carrying

5 a stream of pulverized fuel suspended in carrier air, a peripheral fuel inlet chamber at the inlet end of said tube receiving a stream of fuel from said duct and having an outer wall spaced radially beyond said air discharge opening and 10 beyond the peripheral wall of the burner tube to form an annular fuel passage out of the direct path of the secondary air stream, said outer wall becoming tangential to the wall of said tube to supply said stream of fuel thereto under conditions to cause the stream to rotate peripherally in a layer in said tube, means causing said layer of suspended fuel to advance helically toward the outlet end thereof, whereby at least the major portion of the stream of fuel suspended in carrier 15 air is caused to advance in said tube beyond said inlet chamber before being mixed with the secondary air stream.

10. A pulverized fuel burner comprising a burner tube having an open outlet end adapted to connect with a combustion chamber, tangential fuel inlet means, including an inlet port in the peripheral wall of said tube, supplying to said tube a stream of pulverized fuel suspended in carrier air under conditions to cause said stream to rotate peripherally in said tube, means causing said layer of suspended fuel to advance helically therein, a central axial air admission means admitting a secondary air stream to said tube to advance axially therein and to mix with 20 said fuel stream to form a combustible mixture, and a set of axial vanes mounted in said burner tube near the periphery thereof and positioned to deflect the fuel stream toward the axis thereof so as to distribute the fuel across the outlet end 25 of said tube.

11. A pulverized fuel burner comprising a burner tube with a burner throat at its outlet end adapted to open into a combustion chamber, means supplying to said burner tube, in a direction tangential to the inner surface thereof, a stream of pulverized fuel suspended in carrier air, means causing said suspended fuel to advance helically in a peripheral layer in said tube to the outlet end thereof, and elongated tubular means 30 of a diameter at least as small as the diameter of said burner throat extending into said burner tube from the inlet end thereof for supplying secondary air thereto.
